DESIGN FOR A LIGHTING FIXTURE

Henry Santoro, Richmond Hill, N. Y.

Application November 26, 1940, Serial No. 96,822

Term of patent 3½ years

To all whom it may concern:

Be it known that I, Henry Santoro, a subject of the King of Italy, residing at 103-13 107th Street, Richmond Hill, in the county of Queens, in the State of New York, have invented a new, original, and ornamental Design for Lighting Fixtures, of which the following is the specification, reference being had to the accompanying drawing, forming part thereof.

I claim:

The ornamental design for a lighting fixture, as shown.

HENRY SANTORO.
